UNITED STATES PATENT OFFICE.

CHARLES T. WESTLAKE, OF ST. LOUIS, MISSOURI, ASSIGNOR TO TRANSOM DRAFT GEAR COMPANY, OF ST. LOUIS, MISSOURI, A CORPORATION OF DELAWARE.

TRANSOM DRAFT-GEAR.

1,196,917.

Specification of Letters Patent.

Patented Sept 5, 1916.

Application filed April 9, 1915. Serial No. 20,176.

To all whom it may concern:

Be it known that I, CHARLES T. WESTLAKE, a citizen of the United States, residing at St. Louis, Missouri, have invented a cer-

tain new and useful Improvement in Transom Draft-Gear, of which the following is a full, clear, and exact description, such as will enable others skilled in the art to which it appertains, to make and use the same, reference being had to the accompanying drawings, forming part of this specification, in which—

My invention relates generally to railway car construction and more particularly to a transom draft gear of the friction type, the principal object of my invention being to generally improve upon the construction of the present types of transom draft gears, and to provide a comparatively simple inexpensive construction which can be easily and quickly assembled or taken apart, and which in service will insure a uniform distribution of the buffing and pulling strains through the transom or bolster to the under-frame with which the same is associated.

Further objects of my invention are to construct a transom draft gear which is compact, particularly in transverse dimensions, thereby permitting it to be advantageously utilized in connection with under-frames where the sill members are located comparatively close together; to provide a draft gear with which may be readily combined a friction element of ordinary construction, and to form in the bolster with which the draft gear is associated a follower block pocket, the end walls of which form stops to limit the movement of the follower block as the draft gear moves backward and forward under pulling and buffing strains.

With the foregoing and other objects in view, my invention consists in certain novel features of construction and arrangement of parts, hereinafter more fully described, claimed and shown in the accompanying drawings, in which—

Figure 1 is a plan view of my improved draft gear, the same being combined with a car transom or body bolster. Fig. 2 is a front elevational view of the transom or body bolster of my improved draft gear associated therewith and with the draw-bar extension in vertical section. Fig. 3 is a horizontal section taken approximately on the line 3—3 of Fig. 2. Fig. 4 is a vertical

section taken approximately on the line 4—4 of Fig. 1. Fig. 5 is a horizontal section taken approximately on the line 5—5 of Fig. 4.

In the accompanying drawings, I have shown the draft gear associated with a cast metal transom or bolster, the same comprising a vertically disposed web 10, top plate 11 and bottom plate 12, the latter being provided with the usual center bearing 13.

Formed through the central portion of the web 10 is an opening 14 which receives the draft gear and arranged at the sides of this opening are transversely disposed plates 15 which serve as points of attachment for the center sills 16, which latter extend through suitable openings 17 in the web 10 at the sides of the center opening 14.

Formed integral with the central portion of the top plate 11 and extending longitudinally thereof is a housing 18, the same enclosing a downwardly opening pocket 19 which receives the upper portion of a follower plate 20. The lower portion of this plate occupies a longitudinally disposed pocket 21, the same being formed in the bottom plate 12 between the webs 15. The draw-bar extension 22 forming a part of my improved draft gear is preferably in the form of an elongated hollow member, square in cross section. The forward end of this extension is provided with a pocket 23 which is adapted to receive the rear end of the coupler shank and the rear end of said extension is provided with a plate 24 which normally bears directly against the front face of follower block 20.

Formed in the rear portions of the side walls of the extension are longitudinally disposed slots 25 and passing therethrough is a key 26, the outer end portions of which occupy horizontally disposed notches 27, the same being formed in the front portions of the transversely disposed webs 15. The end portions of this key also pass through longitudinally disposed slots 16^a which are formed in the webs of the center sills 16, and seated in the outer ends of said key are cotters or like key retaining devices. These slots 16^a are greater in length than the width of the key, thus permitting said key to move forward for a limited distance when the device is subjected to pulling strains.

It will be understood that the notches 27 are open at their forward ends, and further that

the slots 25 are greater in length than the width of key 27, and thus said key is free to move forwardly with respect to webs 15 and likewise extension 22 can move rearwardly for a limited distance independently of said key 26.

10 The yoke 28 forming a part of my improved draft gear is preferably formed in a single piece and comprises parallel legs 29, the rear ends of which are connected by a plate 30, the same serving as a seat for the friction device associated with the draft gear.

15 I have shown associated with the draft gear a friction device comprising a cylindrical member 31, the same being provided with a plunger 32 and when said device is properly associated with the draft gear, the rear end of said cylinder bears against plate 30, and the forward end of the plunger bears directly against the rear face of follower block 20.

20 The forward ends of the legs 29 of the yoke are provided with suitable openings 33 which receive the key 26 and formed on or fixed to the rear portions of said legs are vertically disposed ribs or stop lugs 34, the same being adapted to engage the rear ends of webs 15, thereby serving as stops to limit 25 the movement of the yoke as it is pulled forward under pulling strains.

25 In assembling the parts of my improved draft gear, follower block 20 is entered from the rear of the bolster and by tilting said 30 block or shifting it into an inclined position as shown by dotted lines in Fig. 4, it can be manipulated so that its lower portion can be dropped into the pocket 21 and when so positioned, the upper portion of said 35 block bears against the inner face of the front wall of housing 18. The yoke and friction cylinder are now entered from the rear, after which the rear end of extension 22 is positioned between the forward ends 40 of the legs of the yoke and all parts are united by the insertion of key 26 through slots 25, openings 33 and notches 27.

45 Buffing strains imparted to extension 22 are transmitted through follower block 20 to plunger 32 in cylinder 31, which latter bears against the rear end of the yoke, and the latter being held against rearward movement by key 26, the end portions of which bear in notches 27.

50 The rearward movement of the extension under buffing strains is limited and stopped by the engagement of the rear face of follower block 20 against the faces on the body bolster at the rear ends of pockets 19 and 55 21, and which action takes place at the same time the forward ends of slots 25 bear against the front side of key 26. Under pulling strains, extension 22 pulls yoke 28 forwardly for the reason that said parts are 60 connected by key 26, and as a result of such 65

action, plunger 32 is forced into cylinder 31 by reason of the engagement of said plunger against follower block 20, the same bearing against the faces of the walls of the body bolster in front of pockets 19 and 21. The forward movement of the extension and yoke under pulling strains is limited and stopped by the engagement of lugs 34 against the rear ends of webs 15, which action takes place at the same time the front 70 side of key 26 comes in contact with the ends of the slots 16^a in the webs of center sills 16.

75 The type of draft gear herein shown and described is particularly adapted for use on freight cars, although with slight structural changes, it can be advantageously utilized with all types of cars.

80 A transom draft gear of my improved construction is comparatively simple, comprises a minimum number of parts, can be easily and cheaply manufactured, is very compact, can be readily assembled or taken apart, and is very effective in transmitting 85 to the transom and underframe all pulling and buffing strains to which the device is subjected while in service.

90 It will be readily understood that minor changes in the size, form and construction of the various parts of my improved transom draft gear can be made and substituted for those herein shown and described, without departing from the spirit of my invention, the scope of which is set forth in the appended claims.

100

I claim:

1. The combination with a bolster and sills passing therethrough, which bolster is provided with a draft gear opening, of a drawbar, a yoke connected thereto, which yoke passes through the draft gear opening in the body bolster, a yielding resistance element carried by said yoke, a follower block interposed between the yielding resistance element and the end of the drawbar, means on the bolster for limiting the movement of the follower block, and a key seated in the yoke and passing through openings formed in the drawbar and the sills.

105 2. The combination with a bolster and sills passing therethrough, which bolster is provided with a draft gear opening, of a drawbar, a yoke connected thereto, which yoke passes through the draft gear opening in the body bolster, a yielding resistance element carried by said yoke, a follower block interposed between the yielding resistance element and the end of the drawbar, means on the bolster for limiting the movement of the follower block, a key seated in the yoke 110 and passing through openings formed in the drawbar and the sills, and means on the yoke for limiting its forward movement 115 through the bolster.

120 3. The combination with a transom pro-

- vided with a draft gear opening and with pockets above and below said opening, of a draft gear occupying the opening in said transom, a follower block forming a part of 5 said draft gear, the upper and lower ends of which block are positioned in said pockets, and means for limiting the backward and forward movement of the draft gear with respect to the bolster.
- 10 4. The combination with a bolster having a series of openings, of a draft gear occupying one of said openings, sills occupying the other openings, said sills being provided with longitudinally disposed slots, a draw- 15 bar, a key passing through said drawbar, the yoke and the openings in said sills, a follower block forming a part of the draft gear, and pairs of shoulders formed on the bolster above and below the draft gear open- 20 ing for engaging the top and bottom of the follower block to limit the movement thereof in both directions.
5. The combination with a body bolster, having a draft gear opening, of a draw-bar, 25 a yoke connected thereto, a yielding resistance element carried by the yoke, a follower block interposed between the yielding resistance element and the draw-bar, means on the body bolster for limiting the movement 30 of the follower block in both directions, and means for limiting the forward movement of the yoke with respect to the body bolster.
6. The combination with a body bolster provided with a draft gear opening, of a 35 yoke positioned in said opening, a draw-bar, the rear end of which is positioned in said opening, a key forming a connection between the yoke and draw-bar, which key bears against the body bolster, a yielding 40 resistance element carried by the yoke, a follower block interposed between the yielding resistance element and the draw-bar, and means on the bolster for limiting the movement of the follower block.
- 45 7. The combination with a body bolster
- provided with a draft gear opening, of a yoke positioned in said opening, a draw-bar, the rear end of which is positioned in said opening, a key forming a connection between the yoke and draw-bar, which key bears 50 against the body bolster, a yielding resistance element carried by the yoke, a follower block interposed between the yielding resistance element and the draw-bar, means on the bolster for limiting the movement of the 55 follower block, and means for limiting the forward movement of the draw-bar with respect to the bolster.
8. The combination with a transom, of a draft gear comprising a draw-bar, a yoke, a 60 member connecting the draw-bar and yoke, which member is adapted to engage the transom to hold the yoke against movement in one direction, means on the yoke adapted to engage the transom to limit the movement 65 of said yoke in the opposite direction, a yielding resistance element carried by the yoke, a follower block interposed between the yielding resistance element and the draw- 70 bar, and means on the transom for limiting the movement of the follower block in both directions.
9. The combination with a transom draft gear comprising a draw-bar, a yoke connected thereto, a yielding resistance element 75 in the yoke, and a single follower block interposed between the draw-bar and the yielding resistance element, of a transom provided with an opening adapted to receive said draft gear, said transom being provided 80 with pockets above and below the draft gear opening and which pockets receive parts of the follower block.

In testimony whereof I hereunto affix my signature in the presence of two witnesses, 85 this 23rd day of March, 1915.

CHARLES T. WESTLAKE.
